CLAIM

We claim the ornamental design for a mobile phone with
transitional graphical user interface, as shown and described.

DESCRIPTION

(**) Term: **15 Years**

(21) Appl. No.: **29/701,852**

(22) Filed: **Aug. 15, 2019**

(30) **Foreign Application Priority Data**

Feb. 18, 2019 (KR) 30-2019-0007265

FIG. 1 is a first image in a sequence of the first embodiment
of a mobile phone with transitional graphical user interface
showing our new design;

(51) LOC (13) Cl. **14-04**

FIG. 2 is a second image thereof;

(52) U.S. Cl.

FIG. 3 is a first image in a sequence of the second embodiment
of a mobile phone with transitional graphical user interface
showing our new design;

(58) **Field of Classification Search**

FIG. 4 is a second image thereof;

USPC **D14/487**

FIG. 5 is a first image in a sequence of the third embodiment
of a mobile phone with transitional graphical user interface
showing our new design;

USPC **D14/485-495**

FIG. 6 is a second image thereof;

CPC H04M 1/72544; G06T 13/00; G06T 13/80;

FIG. 7 is a first image in a sequence of the fourth embodiment
of a mobile phone with transitional graphical user interface
showing our new design; and,

G06F 3/04845

FIG. 8 is a second image thereof.

See application file for complete search history.

The broken lines in the figures depict portions of the mobile
phone with transitional graphical user interface which form
no part of the claimed design.

(56) **References Cited**

The appearance of the transitional graphical user interface
sequentially transitions between the images shown in FIGS.
1 and 2, FIGS. 3 and 4, FIGS. 5 and 6 and FIGS. 7 and 8,
respectively. The process or period in which one image
transitions to another forms no part of the claimed design.
